MACHINE FOR MAKING WINDOW BAGS**Harold L. Bartelt, Rockford, Ill., assignor of forty-five per cent to Donald E. Bartelt****Application April 14, 1952; Serial No. 282,119****10 Claims. (Cl. 93—8)**

This invention relates to machines for making window bags of the type in which a window cut in one wall of the bag is covered by a piece of transparent material sealed to the wall around the window. The invention also has reference to an automatic bag making machine, such as the one disclosed in my prior application Serial No. 98,660, filed June 13, 1949, now Patent No. 2,649,674, in which the bags are made in a series from strips of material fed endwise along a predetermined path and in which the bag making operations are performed at stations disposed along the path.

The principal object is to adapt such an automatic bag making machine for producing a window bag of the above character and to utilize several of the mechanisms of the prior machine in adding the piece of transparent material.

Another object is to utilize the mechanisms of the prior machine in a manner to position the transparent piece automatically with respect to the window without the addition of special synchronizing devices.

A more detailed object is to cut the windows in one of the strips at a station along the bag forming path and to form the window piece from a transparent strip which is advanced alongside the window strip and joined to the latter around the windows so that the strip is advanced along the path by the feeding mechanism of the bag forming machine and is cut to the proper size by the same cutter which separates the bags after formation thereof.

The invention also resides in the novel construction and arrangement of the mechanisms used to cut the windows and to seal the transparent strip to the bag walls.

Other objects and advantages of the invention will become apparent from the following detailed description taken in connection with the accompanying drawings, in which:

Figure 1 is a side elevation with parts broken away of a bag machine constructed in accordance with the present invention.

Fig. 2 is a partial left end view.

Figs. 3 and 4 are sectional views taken along the lines 3—3 and 4—4 of Fig. 1.

Fig. 5 is a sectional view taken along the line 5—5 of Fig. 4.

Fig. 6 is a schematic perspective view illustrating the order in which the bag making operations are performed.

Fig. 7 is a perspective view of the strips used in making the bags with parts of the strips broken away.

Fig. 8 is a sectional view taken along the line 8—8 in Fig. 6.

Fig. 9 is a fragmentary perspective view of the window punch.

For the purposes of illustration, the drawings show a window bag 10 (Figs. 6 and 8) adapted to be made by a machine constructed in accordance with the present invention and comprising two flexible walls 11 and 12 of sheet material closed at the bottom as by a fold and sealed as indicated at 13 along the side edges. The window is formed by a hole 14 punched in the central portion of the wall 11 and covered by a transparent piece 15 of material

2

lying against the inner side of the wall and sealed to the latter around the entire periphery of the hole as indicated at 16.

As shown, the invention is embodied in an automatic bag making machine such as the one disclosed in the above mentioned application to which reference may be had for further details. In general, such machines form the bags from strip material in a succession of operations which may consist in folding a sheet 17 (Fig. 1) of wall material longitudinally as it is advanced step by step along a rectilinear path whereby to form two strips 18 and 19 (Fig. 6) disposed face to face, cross-sealing the strips at a station 20 to join the two by a seal 13a wider than the side seals 13, and severing the cross-seal 13a intermediate its edges at a cutting station 21 thereby completing the making of the bag. As disclosed in the aforesaid application, the bags may be filled at a station 22 and closed at a final station 23 in the continued step by step movement of each completed bag.

The various mechanisms for advancing and forming the bags 10 are all mounted on a frame 24 and are actuated by a common camshaft 25 extending along the frame parallel to the path of the bags and journaled in suitable bearings, such as shown at 26, to be driven continuously through a belt 27 from a motor 28. The feeding mechanism for advancing the strips 18 and 19 endwise comprises two rollers 29 and 30 which engage the outer sides of the strips and are driven intermittently through a gear box 31 by a shaft 32 connected to the camshaft 25 through an indexing mechanism 33. The latter may include a link 33a driving the shaft 32 through a one way clutch 33b such as shown in the application of Kenneth R. Johnson, Serial No. 261,226, filed December 12, 1951, and is effective during each revolution of the camshaft to drive the shaft 32 and hence the rollers 29 and 30 until a photocell 34 detects the presence of a mark on the strip 18 and energizes a brake 32a to stop the shaft 32 and the rollers. The spacing of the marks, which may conveniently be one edge of the windows 14, is such that the strips are advanced through a distance corresponding to the width of the bags being formed.

To form the strips 18 and 19, the continuous sheet 17 of bag material is unwound by the feed rollers 29 and 30 from a roll 35 mounted on the frame 24 at one end of the machine, advanced overstraightening rollers 36 mounted on arms 37 and 38 projecting outwardly from the frame end and fed through a mechanism 39 by which the sheet is folded longitudinally. From the folding mechanism, the strips are advanced through the cross-sealing station 20 where, during a dwell of the strips, the transverse seal 13a is made to form the bags 10. Preferably, the strips are heat sealed and, for this purpose, are composed of or coated on their inner surfaces with a material which will soften when heated above a predetermined temperature and enable selected areas of the strips, when pressure is applied, to fuse together and become integrally joined. Polyethylene or materials sold under the trade names of Pliofilm and Cellophane are examples of the numerous materials suitable for this use.

To effect the cross-sealing, a shoe 40 (Fig. 5) heated to a temperature sufficient to soften the bag material is secured to the upper half 41 of a vertical lever 42 which is disposed at the sealing station 20 and is pivoted intermediate its ends by a sleeve 43 (Fig. 4) integral with the lever 42 and journaled on a shaft 44 so that the shoe may be swung toward the strips 18 and 19 to press them against a shoe 45 on a backing member 46 (Figs. 3 and 4). The latter is behind the strips with the shoe 45 facing outwardly toward the shoe 40 and is yieldably mounted on a bracket 47 upstanding from the frame 24 by a bolt 48 projecting loosely through the bracket and threaded into the back of the member 46 with a spring 49 acting

between the member and the bracket. During a dwell of the strips, the rise of a cam 50 on the camshaft 25 engages a follower roller 51 carried at the lower end of the lever 42 turning the latter about its pivot against the force of a contractile spring 51^a, which acts between the frame 24 and the lower end of the lever, and swinging the shoe forward to cross-seal the strips.

Severance of the bags 10 is accomplished herein by two vertical opposed blades 52 and 53 disposed on opposite sides of the strips 18 and 19 and located beyond the feed rollers 29 and 30 at the cutting station 21. The blade 53 is stationary on the frame 24 and the other blade 52 is mounted on the upper end of an upright lever 54 pivoted intermediate its ends on a rock shaft 55. During dwelling of the strips, the rise of a cam 56 on the camshaft 25 engages a follower 57 journaled on the lower end of the lever 54 rocking the latter and swinging the blade 52 toward the blade 53 to cut the strips between the edges of the seal 13^a.

As more fully set forth in my prior application, the machine thus far described operates in successive cycles each comprising one revolution of the camshaft 25 to complete the formation of one bag and cut the same off from the leading end of the strip. In the first part of the cycle, the rollers 29 and 30 are turned to draw material from the roll 35 past the folder 39 and advance the folded strip a distance equal to the width of the bag as determined by the photocell controlled mechanism 33. During the ensuing dwell of the strip, the heated shoe 40 and the cutter 52 are advanced simultaneously to form the cross seal 13^a at the station 20 and sever the previously formed seal at the station 21.

In accordance with the present invention, the strip feeding, seal actuating and cut-off mechanisms of the bag forming machine are utilized advantageously to perform the additional functions of forming the window sheet 15, locating the same properly with respect to the window opening 14, sealing the sheet to the wall 11 around the window, and cutting the sheet to a desired length. To accomplish this, a strip 59 of transparent window material is placed alongside the strip 17 before folding of the latter so that the window strip becomes attached to the folded strip by the cross seal 13^a and is thus held properly positioned relative to the window 14 preparatory to sealing of the window strip to the outer strip 18 at a subsequent sealing station 60.

In order that the transparent strip 59 may enter the bag forming path in the proper relation to the strips 18 and 19, a roll 61 (Figs. 1 and 2) of transparent strip material is carried on the ends of the arms 37 above the roll 35 where it is unwound and advanced over the straightening rollers 36 alongside the sheet 17 of bag material. The roll 61 is supported by a horizontal shaft 62 the ends of which are journaled in brackets 63 rigid with and depending from the outer ends of the arms 37. Preferably the transparent strip 59 is somewhat less than half as wide as the sheet 17 and is unwound with its left edge, as viewed in Fig. 2, lying along the center of the sheet. The proper relation of the strip and the sheet is obtained by placing the roll 61 on the right side of the shaft 62 and holding it in that position by collars 64 which abut against the ends of the roll and are secured to the shaft by set screws 65.

From the rolls 35 and 61, the sheet 17 and the transparent strip 59 are advanced over the folding mechanism 39 where the sheet is folded longitudinally. Since the transparent strip lies over only one side of the sheet (Fig. 6), it is not folded and, upon leaving the folding mechanism, is disposed between and parallel to the strips 18 and 19 formed by the fold as shown in Figs. 7 and 8.

To form the window 14, a cutter or punch 66 is disposed at a station 58 between the folding mechanism 39 and the cross sealing station 20 where it may be operated by the camshaft 25 during each dwell of the strips 18 and 19 to cut the window in the strip 18. Herein, the

punch comprises a male die 67 (Fig. 3) on the inside of the strip 18 and a female die 68 on the outside, the two dies having complementary cutting surfaces which, when moved together, punch out the hole 14. In the present instance, the hole is generally square and hence the cutting surfaces of the dies are also square as will be seen in Fig. 1.

The male die 67 is mounted on the front of a flat vertical plate 69 projecting downwardly between the strip 18 and the transparent strip 59 from a horizontal arm 70 fast on an upright bracket 71 which is suitably bolted to the frame 24. Since the window cutting station 58 is in advance of the cross sealing station 20, the strip 18 is free to pass in front of the plate 69 while the strips 19 and 59 pass behind and, therefore, the plate does not interfere with the advance of the strips. The female die 68 is supported by a rigid vertical plate 72 carried on the upper end of an upright lever 73 pivoted intermediate its ends on a shaft 74 secured to the frame. Acting between the frame and the lower portion of the lever is a contractile spring 75 which normally urges the female die away from the male die and holds a follower roller 76 journaled on the lower end of the lever against a cam 77 on the camshaft 25. While the strips are dwelling and the cross sealing and cut-off operations are being performed, a rise 78 of the cam engages the follower roller to swing the lever and move the female die toward the male die thus punching out a portion 79 of the strip 18 to form the window. During the cutting, the plate 69 is held against lateral shifting or bending by a vertical idler roller 80 journaled on the bracket 71 near the bottom of the plate and bearing against the latter through the strips 19 and 59 to serve as a backing.

The cut out portion 79 is ejected through a hole 81 formed in the plate 72 and aligned with the dies 67 and 68. If desired, the ejection may be assisted by air jets flowing from horizontal passages 82 (Fig. 3) formed in the male die and communicating with a compressed air supply line 83 through a vertical passage 84 in the plate 69. A valve 85 (Fig. 1) is interposed in the supply line and is actuated by a cam 86 on the camshaft 25 in timed relation with the swinging of the lever 73 so that compressed air is admitted to the passages 82 immediately after the portion 79 is punched out by the dies.

In order that the strip 18 may ride over the male die 67 during the next advance without being torn around the window 14 by the die, stripper 67^a (Fig. 9) are disposed along the opposite side edges of the die and serve to guide the strip outwardly around the cutting edges of the die. As shown, the strippers 67^a are in the form of strips riveted to the plate 69 along their outer edges with their inner edges 67^b bent outwardly to lie alongside and flush with the side edges of the die. When the lever 73 swings the female die 68 forwardly, the latter depresses the stripper edges 67^b permitting the dies to punch the window and, as the female die is retracted, the stripper edges spring out even with the male die to present a smooth continuous surface over which the strip 18 moves during the next advance by the feed rollers 29 and 30.

From the punching station 58, the strips 18, 19, and 59 are advanced to the station 60 between the photocell 34 and the cross-sealing station 20 where the seal 16 joining the transparent strip 59 to the strip 18 around the window 14 is formed. To form this seal, the areas of the strip 18 surrounding the window and the corresponding areas of the transparent strip are pressed together between two sealing elements 87 and 88 (Figs. 4 and 5) disposed at the station 60. In the present instance, the sealing element 87 is a flat hard rubber plate vertically suspended from a horizontal arm 89 projecting forwardly from the bracket 47 upstanding from the frame 24 and projects into the bag forming path between the transparent strip 59 and the strip 19. The other element 88 comprises a vertical plate 90 with laterally projecting

shoes 91 having sealing surfaces facing the rubber plate 87. The sealing surfaces are arranged to form a square aligned with and corresponding in size and shape to the areas of the strips 18 and 59 joined by the seal 16. Electrical heaters 92 are embedded in the plate 90 to heat the shoes 91 above the fusing temperature of the bag material so that, when the sealing element 88 is moved to press the strips 18 and 59 against the surface of the rubber plate, the strips are fused together.

The sealing element 88 is mounted on the upper end of a vertical lever which is rocked by a cam on the cam-shaft 25 to swing the shoes 91 toward the rubber plate 87. Preferably this sealing element is carried by the same lever 42 which supports the shoe 40 and, for this purpose, is secured to the upper end of a second arm 93 rigid with and upstanding from the sleeve 43 alongside and in advance of the lever arm 41. To make the lever assembly more rigid, the shoes 40 and 91 and the plate 90 may be formed as a single piece 94 which is mounted on the arms 41 and 93 by bolts 95 projecting loosely through the arms and threaded into the back of the plate 90. Springs 96 surrounding the bolts and acting between the arms and the plate permit yielding of the latter so that the shoes 40 and 91 will engage the strip 18 firmly when pressing the strips being sealed against the sealing element 87.

To maintain the rubber plate 87 in its vertical position when the seal 16 is being formed, a backing plate 97 is disposed in back of the rubber plate on the outside of the strip 19 and acts through the latter to hold the rubber plate against any substantial lateral shifting. The backing plate is supported by the same bracket 47 which supports the backing member 46 and is yieldably mounted on the bracket by bolts 98 and springs 99 in the same manner as the backing member 46 is mounted.

With the transparent strip 59 attached to the strip 18, the feed rollers 29 and 30 unwind a length of the transparent strip corresponding to the length of bag material 17 unwound from the roll 35 and advance the transparent strip concurrently with the wall strips 18 and 19. Thus each portion of the strip 59 which is to form one of the transparent pieces 15 is maintained in alinement with its associated window 14 by the same mechanism which advances the strips 18 and 19. With this construction, the transparent piece is moved along the path of the machine in exact synchronism with the bag walls 11 and 12 without the use of additional feed mechanism.

When the bags 10 reach the cutting station 21, the transparent strip 59 is cut into lengths corresponding to the width of the transparent pieces 15. By making the transparent pieces of the same width as the bags, the blades 52 and 53 may be used to cut the strip since the latter passes between the blades with the strips 18 and 19. Thus, when the blade 52 is swung forward, the transparent piece is cut from the strip 59 at the same time that the end bag is severed from the strips 18 and 19.

In the operation of the machine, the sheet material 17 is unwound from the roll 35 and drawn over the folding mechanism 39 to form the two strips 18 and 19. Since the transparent strip 59 is joined to the strip 18 by the seals 13^a and 16, it is unwound from the roll 61 at the same time and in synchronism with the sheet material 17. With the transparent strip lying over only one side of the sheet material, it is not folded as it passes through the folding mechanism and is disposed between and parallel to the strip 18 and 19 upon completion of the folding operation. During each revolution of the cam-shaft 25, the three strips are advanced together by the feed rollers through a distance corresponding to the width of the bags 10 and then, due to the operation of the indexing mechanism 33 and the brake 32^a, are stopped.

While the strips are dwelling, the rise of each of the cams 77, 50, and 56 engages its respective follower roller swinging the levers 73, 42, and 54. Thus the female die 68 is swung toward the male die 67 and cuts a window 14

in the strip 18 and, as the female die is retracted by the spring 75, the cam 86 actuates the valve 85 to permit compressed air to flow through the jet orifices 82 and eject the cut-out portion 79. While one window is being cut out, the shoes 91 seal the strip 18 to the transparent strip 59 around another window which had previously been cut and advanced to the station 60 and the shoe 40, being on the same lever 42 as the shoes 91, swings forward with the latter and cross-seals the three strips between the window being sealed and the window which was sealed during the previous cycle. At the same time, the blades 52 and 53 cut the window sheet 15 from the transparent strip and sever the bag 10 at the leading end of the strips. After these operations have been completed, the indexing mechanism 33 again is effective to turn the feed rollers 29 and 30 and advance the three strips through a distance equal to the width of the bags and, during a subsequent dwell of the strips, the above operations are repeated.

It will be seen that a standard bag making machine has been adapted to cut the windows 14 in the bags 10, cut the window sheets 15 to the proper size, position the sheet accurately with respect to the window and seal the sheet to the wall 11 around the window by the addition of only three simple mechanisms, namely, the shaft 62 and its support for mounting the roll 61 of transparent strip material 59, the punching mechanism 66 and the sealing elements 87 and 88. By using the feed rollers 29 and 30 and the knife blades 52 and 53 which advance and cut the strips 18 and 19 to feed and cut the transparent strip 59, the transparent window sheet 15 is positioned automatically with respect to the bag walls 11 and 12. This synchronized movement of the strips achieves a high degree of accuracy and, as a result, the transparent sheet is always centered relative to the window 14 so that the bags 10 are neat and well formed. In addition, such accuracy is obtained without the use of special synchronizing mechanisms by utilizing the mechanisms already present in the standard machine.

I claim as my invention:

1. A bag making machine comprising, means for supporting a first strip of material and guiding the same endwise along a predetermined path, mechanism for supporting a transparent strip alongside said first strip, means disposed along said path and operable to fold said first strip longitudinally around said transparent strip, rollers disposed in said path beyond said folding means and engageable with opposite sides of said folding strip, an actuating mechanism for turning said rollers periodically to advance said folded strip in successive steps through distances corresponding to the width of the bags to be formed, sealing elements disposed along said path and engageable during dwelling of said strips with the opposite sides of said folded strip to seal the same to said transparent strip transversely of the strips, means including a cutter disposed along said path and operable during a dwell of the strips to cut a window in one side of said folded strip, and sealing members beyond said cutter and engageable with said one side and said transparent strip to seal the same together around the window.

2. Apparatus for making bags from two outside wall strips and an intermediate transparent strip, said apparatus having, in combination, mechanism for supporting the three strips of material side by side and advancing the same endwise along a predetermined path through distances corresponding to the width of the bags to be formed, means including a cutter disposed along said path and operable to cut a window in one of the outside strips during dwelling of the strips, sealing elements disposed along said path beyond said cutter and engageable with said transparent strip and said one outside strip to seal the two strips together about the window, sealing members disposed beyond said cutter and engageable with said outside strips to seal the same to said middle

strip transversely of the strips and between said windows thereby to form a bag, and a second cutter disposed along said path and beyond said sealing members and operable to cut said strips intermediate the edges of the transverse seal.

3. Apparatus for making bags from two outside wall strips and an intermediate transparent strip, said apparatus having, in combination, mechanism for supporting the three strips of material side by side and advancing the same endwise along a predetermined path through distances corresponding to the width of the bags to be formed, means including a cutter disposed along said path and operable to cut a window in one of the outside strips during dwelling of the strips, sealing elements disposed along said path beyond said cutter and engageable with said transparent strip and said one outside strip to seal the two strips together about the window, and sealing members disposed beyond said cutter and engageable with said outside strips to seal the same to said middle strip transversely of the strips and between said windows thereby to form a bag.

4. In a bag making apparatus, the combination of, means for supporting a first strip of material and guiding the same endwise along a predetermined path, means disposed in said path and operable to fold said strip longitudinally, rollers disposed in said path beyond said folding means and engageable with opposite sides of said folded strip, an actuating mechanism for turning said rollers periodically to advance said strip in successive steps through distances corresponding to the width of bags to be formed, means including a cutter disposed along said path and movable into engagement with said strip to cut a window in the same, means for guiding a strip of transparent material endwise along said path and over said windows, sealing elements disposed along said path and engageable with the opposite sides of said first strip to seal the same and said transparent strip together between said windows whereby said rollers advance said transparent strip with said first strip, and sealing members beyond said cutter and engageable with both of said strips to seal the same together around said windows.

5. In a bag making machine having a plurality of stations successively disposed along a predetermined path, the combination of, a die member disposed at one of said stations and projecting into said path, a sealing member projecting into said path at a subsequent station, mechanism for supporting and advancing two strips of outside wall material and an intermediate transparent strip side by side through successive steps along said path with a first outside strip passing in front of said members, the second outside strip passing behind said members and the middle strip passing behind said die member and in front of said sealing member, a complementary die disposed in front of said die member and movable into engagement with the same to cut a window in said first outside strip, a sealing element disposed in front of said member and movable into engagement with said first outside strip to press the same and said middle strip against the member and seal the strips together around said window, and means to move said die and said sealing element during dwelling of said strips.

6. Bag making apparatus having, in combination, means for supporting two strips of outside wall material and an intermediate transparent strip side by side and advancing the same endwise in successive steps along a predetermined path, means including a cutter disposed along said path and operable during a dwell of the strips to cut a window in one of the outer strips, a member disposed along said path beyond said cutter and projecting between the transparent strip and said one outer strip, said member having sealing surfaces facing said one outer strip and corresponding in size and shape to the edges of the one outer strip around the window, a sealing element disposed adjacent said member and on the outside of the

other of said outer strips and having a sealing surface facing the strips and extending transversely of the same, a sealing unit disposed on the outside of said one outer strip and movable toward and away from the strips, said unit having complementary sealing surfaces opposing the surfaces on said member and a sealing surface opposing and complementing the surface on said element, and means operable during dwelling of the strips to move said sealing unit against said strips to seal the three strips together transversely and to seal the one outer strip and the transparent strip together around a window.

7. In a bag making machine having stations successively disposed along a predetermined path, the combination of, mechanism for supporting two strips of outside wall material and an intermediate transparent strip side by side and advancing the same endwise along said path in successive steps, means including a cutter at one of said stations and operable during a dwell of said strips to cut a window in one of the outside strips, a sealing member disposed at a subsequent station and projecting into said path and between the other outside strip and said transparent strip, a sealing element disposed at said last mentioned station and movable toward the strips to press said one outside strip and said transparent strip against said sealing member and seal the two strips together around said window, and means operable during a dwell of the strips to move said sealing element toward said sealing member.

8. In a machine for making window bags, the combination of, means for supporting a first outside strip having windows formed therein at intervals of a predetermined distance, a second outside strip and an intermediate transparent strip in side by side relation, mechanism for advancing said strips endwise and intermittently through said predetermined distance, a member disposed along the path of said strips and projecting in between the other of said outside strips and said transparent strip, a second member disposed on the outside of said window strip and opposing said first member, said members having complementary sealing surfaces aligned during dwelling of the strips with the edges of said windows, and means operable during dwelling of the strips to move said members together thereby to press said window strip and said transparent strip between said sealing surfaces and seal the two strips together around the window.

9. In a bag making machine having stations successively disposed along a predetermined path, the combination of, mechanism for supporting two strips of outside wall material and an intermediate transparent strip side by side and advancing the same endwise in successive steps along said path, a stationary member disposed at one of said stations and projecting between the transparent strip and one of the outer strips, a die bodily supported on said member and having cutting surfaces facing said one outer strip, a movable die disposed at said one station and having cutting surfaces opposing and complementing the surfaces on the stationary die, means operable during dwelling of the strips to move said movable die toward said stationary die thereby to cut a window in said one outer strip, and sealing elements disposed at a subsequent station and engageable with the outer strips between the windows to seal the outer strips to the transparent strip thereby to form bags.

10. In a bag making machine having stations successively disposed along a predetermined path, the combination of, means for supporting two strips of material side by side, mechanism for advancing said strips endwise along said path step by step through distances corresponding to the width of the bags to be formed, a member disposed at one of said stations and projecting between said strips, a die bodily supported on said member and having cutting surfaces facing one of said strips, a movable die disposed at said one station and having cutting surfaces opposing and complementing the surfaces of the die on said member, means operable during

dwelling of the strips to move said movable die toward said other die thereby to cut a portion out of said one strip, and sealing elements disposed at a station subsequent to said first station and engageable with said strips to seal the same together transversely thereby to form bags.
